(57) **CLAIM**

The ornamental design for a faucet, as shown and described.

DESCRIPTION

In a preferred embodiment, the nature of this product is as a plumbing fixture in the form of a spray faucet primarily useful for washing various objects.

FIG. 1 is a left, bottom, front perspective view of a faucet embodying our new design;

FIG. 2 is a left side elevational view thereof, the right side elevational view being a mirror image of the left side shown;

FIG. 3 is a front elevational view thereof;

FIG. 4 is a rear elevational view thereof;

FIG. 5 is a top plan view thereof;

FIG. 6 is a bottom plan view thereof;

FIG. 7 is a left, bottom, front perspective view of a second embodiment;

FIG. 8 is a left side elevational view thereof, the right side elevational view being a mirror image of the left side shown;

FIG. 9 is a front elevational view thereof;

FIG. 10 is a rear elevational view thereof;

FIG. 11 is top plan view thereof;

FIG. 12 is a bottom plan view thereof;

FIG. 13 is a left, bottom, front perspective view of a third embodiment;

FIG. 14 is a left side elevational view thereof, the right side elevational view being a mirror image of the left side shown;

FIG. 15 is a front elevational view thereof;

FIG. 16 is a rear elevational view thereof;

FIG. 17 is a top plan view thereof; and,

FIG. 18 is a bottom plan view thereof.

The broken line representations of a button cap in FIGS. 1, 3, 7, 9, 13, and 15, of holes in FIGS. 1-3, 5-9, 11-15, and 17-18, and of a fitting in FIGS. 1-4, 6-10, 12-16, and 18, are for the purpose of illustration only, and form no part of the claimed design.
